CLAIM

The ornamental design for a lid, as shown and described.

DESCRIPTION

FIG. 1 is a top perspective view of a lid showing the claimed design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the lid that form no part of the claimed design. The dot-dash broken lines in the figures show boundaries that form no part of the claimed design. The shade lines in the figures show contour and not surface ornamentation.

1 Claim, 5 Drawing Sheets(56)
